SHOE PRESS

John Frederick Smith, Quincy, Mass., assignor
to Campo Shoe Machinery Corporation, New
York, N. Y., a corporation of Delaware

Application October 30, 1937, Serial No. 171,854

12 Claims. (Cl. 12—33)

This invention relates to shoe presses for use in shoe manufacturing operations such as cement sole affixing, sole conforming or leveling, channel laying and the like.

5 A general object of the invention is to provide a shoe press which is capable of being rapidly and efficiently loaded and unloaded, is well suited for applying pressure to a shoe sole in the required manner without undue bulging of its pressure applying diaphragm, and at the same time 10 is adapted to accommodate widely varied sizes.

More specifically it is an object of the invention to provide such a shoe press which is capable of controlling the pressure applied to a shoe sole, 15 particularly in the area defining the forepart portion of a shoe, and thereby to prevent rolling of the sole edges by restricting the expansion of the pad with which such presses are equipped by means of a confining plate which is simultaneously 20 adjustable with an adjustable toe post and operates in conjunction therewith.

A further object of the invention is to provide a novel combined toe post and pad confining plate having a rugged construction including 25 means constantly to reinforce the confining plate during operation and additionally to reinforce the toe post when very small sizes are being run.

Other objects of the invention will in part be 30 obvious and will in part appear hereinafter.

The invention accordingly comprises the features of construction, combination of elements, and arrangement of parts, which will be exemplified in the construction hereinafter set forth and the scope of the invention will be indicated 35 in the claims.

For a fuller understanding of the nature and objects of the invention, reference should be had to the following detailed description taken in connection with the accompanying drawings, 40 in which:

Fig. 1 is a side elevation of a shoe press embodying features of the present invention, parts thereof being shown in section better to illustrate the construction;

45 Fig. 2 is a plan view taken substantially along the line 2—2 of Fig. 1 illustrating the adjustable confining plate.

Fig. 3 is a side elevation of a toe post holder and toe post extension member as seen in Fig. 1 and to which the confining plate illustrated in 50 Fig. 2 is attached.

Figs. 4, 5 and 6 are front, top and rear views of the structure shown in Fig. 3.

The present invention is capable of accommodating 55 a wide range of shoe sizes in that its

heel and toe posts are readily adjustable. In conjunction with this adaptability to size range it is also capable of controlling the expansion of the pressure applying pad by means of a confining member movable with the toe post so as to 5 eliminate need for any independent adjustment thereof.

Referring more particularly to the drawings, there is shown in Fig. 1 a press comprising a base 10 which is pocketed so as to receive a pad 11 of any suitable type. Preferably such pad is sufficiently vertically expandable to compensate for ordinary variations in last sizes through inflation alone. A bow member 12 preferably is integrally cast with the press base and extends 15 longitudinally thereover. However, this member may be otherwise associated with the base and may even be movably mounted thereon while retaining certain benefits of the invention. The under side of the bow member adjacent its forward end has integrally cast therewith a downwardly extending web 13, and a toe post guide 14 attached to the underside of the web 13. A toe post comprising a holder portion 15 and a post proper 15' which is adjustably threaded therein 20 is slidably mounted on such guide, the upper end thereof being grooved and provided with attaching plates 16 in order to provide a dove-tail connection with the guide. A set screw 17, provided with a suitable hand wheel 18, is mounted 25 in the toe post in position to clamp against the guide 14 so as to hold the toe post in any chosen position. The underside of the toe post is provided with a shoe contacting pad of rubber or like material.

35 Preferably integrally cast with the toe post is a forwardly and downwardly extending toe post extension member indicated generally at 19. For convenience in operation, this member is bifurcated forming legs 20 and terminating in longitudinally extending feet 21. Carried by the toe post extension member 19 and firmly secured in any suitable manner, as by machine screws 22 passing through the feet 21, is a substantially U-shaped pad confining plate 23. Two lugs or 40 ears 24, preferably integrally cast with the rearward ends of the plate 23, extend downwardly on each side of and below the base member 10 where they are joined by a tie rod 25 which lies contiguous the horizontally arranged bottom 45 faces of reinforcing webs on the underside of the base, all of which serve to prevent upward displacement of the plate 23 and keep it in proper alignment but allow free longitudinal movement thereof.

35

40

45

55

As an additional reinforcing means to the confining plate 23, and particularly to the toe post 15, there is provided a horizontally extending tail piece 26, itself suitably reinforced by a web 27 which branches out following the contour of the bifurcated toe post extension member 20. As the toe post approaches the rearward end of the guide way 14, or even goes partially beyond it, during a run of very small sizes, the tail piece 26 bears against the undersurface of the guide way 14 thereby providing a firm seat against the bow member guide which together with the lugs 24 and tie rod 25 serves firmly to hold the parts against pad imposed stresses.

The press of the present invention is also equipped with a suitably adjustable heel post indicated generally at 27 which may desirably be of the kind more fully described in a copending application Serial No. 32,691, filed July 23, 1935 which matured into Patent No. 2,116,967 granted May 10, 1938. Other known or desired types of heel posts may, of course, be employed.

In operation, the toe and heel posts are adjusted to a proper position to permit insertion of a lasted upper and an outsole between them and the pad 11. The pad is thereafter inflated in the usual manner, pressing the sole against the shoe and pressing the shoe and its last against the toe and heel posts respectively. When shoes of a markedly different size are to be operated on the toe and heel posts may be adjusted so as to accommodate them. Regardless of the size range to be accommodated the confining plate is always in proper alignment and spaced relation with respect to the toe post to control expansion of the pad in the region bordering the forepart area of a shoe thereby to prevent rolling or curling of its sole edges. Any adjustment of the toe post provides proper simultaneous adjustment of the confining plate without further concern on the part of the operator, and a firm support of the confining plate and toe post is assured in all positions.

While the presently described embodiment provides a preferred and practical form of the invention, it should be understood that it is illustrative, and that various changes may be made without departing from the invention described and claimed.

It will thus be seen that there has been provided a shoe press which is well suited to fulfill its intended functions and since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A shoe press comprising a base member, a bow member extending thereover, a heel post carried by said bow member, a pressure applying pad on said base member, an adjustable toe post carried by said bow member, a toe post extension member having a reinforcing element for said toe post engageable in supported relation with said bow member, confining plate means con-

nected to said extension member and adapted to control expansion of said pad, and means movably coupling said confining plate means and said base member to prevent upward displacement of the plate means. 5

2. A shoe press comprising a base member, supporting means connected thereto, a heel post carried by said supporting means, a pressure applying pad carried by said base member, a movable toe post carried by said supporting means, a toe post extension member, a plate connected to said extension member to confine expansion of said pad, lugs connected to said plate extending below said base member and a tie rod secured to said lugs beneath said base member additionally to hold said plate against upward movement. 10

3. A shoe press comprising a base member, supporting means connected thereto, a heel post carried by said supporting means, a pressure applying pad carried by said base member, a movable toe post carried by said supporting means, a toe post extension member having a reinforcing element for said toe post, a plate connected to said extension member to confine expansion of said pad in its forepart area, lugs connected to said plate extending below said base member and a tie rod secured to said lugs beneath said base member additionally to hold said plate against upward movement. 15

4. A shoe press comprising a base member, supporting means connected to and extending over said base member, a heel post carried by said supporting means, a pressure applying pad carried by said base member, a toe post guide member carried by said supporting means, a toe post slidably mounted on said toe post guide member, a bifurcated toe post extension member integral with said toe post, a reinforcing tail piece integral with said extension member and adapted to bear against the under surface of said toe post guide member as said toe post is moved rearwardly with respect to said guide member, a U-shaped confining plate connected to said extension member adapted to embrace the forepart of a shoe and to restrict expansion of said pressure pad in its forepart area, and lugs depending from said confining plate below the underside of said base member and linked by a connecting member passing beneath said base member additionally to hold said confining plate against upward movement. 30

5. A toe post adapted to be movably mounted on a shoe press over a pressing diaphragm, said post having a confining plate attached thereto for movement therewith and extending therebelow in position to engage and restrain the rolling action of such diaphragm adjacent the forepart of a shoe held under said post, and means for tying said plate to the press with a loose motion connection permitting longitudinal plate movement while preventing upward vertical plate movement. 40

6. A toe post adapted to be movably mounted on the bow member of a shoe press over a pressing diaphragm, said post having a downwardly extending member attached thereto and terminating in a confining plate arranged to engage and restrain the rolling action of such diaphragm, and thrust transmitting means on said member in addition to and extending away from said toe post for bearing in supported relation against said bow member at a point spaced from said toe post. 50

7. A toe post adapted to be movably mounted 75

- on the bow member of a shoe press over a pressing diaphragm, said post having a downwardly extending member attached thereto and terminating in a confining plate arranged to engage and restrain the rolling action of such diaphragm, means on said member in addition to said toe post for bearing in supported relation against said bow member and means on said plate for anchoring it directly to a press base.
- 5 10. 8. In a shoe press having a pad carrying base and shoe supporting means positioned above said pad and base, a pad restraining plate shaped to embrace the forepart of a shoe on said pad and positioned to engage and restrain the rolling action of said pad, lugs extending downwardly from opposite sides of said plate beneath said base, and means passing under said base and connecting said lugs to anchor said plate against upward movement with respect to said base.
- 15 20. 9. In a shoe press the combination comprising, a toe post slidably mounted on said bow member, a pad carrying base having a bow member extending thereover, a bifurcated extension member movable with said toe post, a reinforcing tail piece integral with said extension member adapted to seat in supported relation against said bow member, a U-shaped confining plate connected to said extension member in position to restrain the rolling action of said pad, and lugs depending from said confining plate below the underside of said base member and linked by a connecting element passing beneath said base member additionally to hold said confining plate against upward displacement.
- 25 30. 35. 10. A shoe press comprising a base member having longitudinally extending supporting
- means thereover, a pressure applying pad carried by said base member, a toe post slidable along said supporting means, a pad confining plate overlying said pad in the vicinity of said toe post, a plate support connecting said plate and said toe post, and a reinforcing tail piece on said support extending away from said toe post and bearing against said longitudinally extending supporting means.
- 5 10. 11. A shoe press comprising a base member having longitudinally extending supporting means thereover, a pressure applying pad carried by said base member, a toe post movable along said supporting means, a pad confining plate overlying said pad in the vicinity of said toe post, a plate support extending forwardly and downwardly from said toe post to said plate, and means associated with said support for transmitting forces from said plate directly to said supporting means at a point located forwardly of 20 said toe post.
- 15 20. 12. A shoe press comprising a base member having longitudinally extending supporting means thereover, a pressure pad carried by said base member, a toe post guide member extending along said supporting means, a toe post slidably mounted on said guide member, a U-shaped pad confining plate overlying said pad around the toe portion of a shoe held beneath said post, and plate supporting means suspending said plate 30 from said toe post including a thrust transmitting reinforcing tail piece projecting forwardly from said toe post and slidably bearing against said guide member.

JOHN FREDERICK SMITH. 35
